DICTATOR'S STATION MARKING
MECHANISM

Henry P. Clausen, White Plains, N. Y., assignor to
The Gray Manufacturing Company, Hartford,
Conn., a corporation of Connecticut

Application December 4, 1940, Serial No. 368,497

14 Claims.

(CL. 274—9)

This invention is concerned with mechanism by means of which a dictator, in operating a dictation recording machine from a point remote with respect to the recording machine, may be provided with marking apparatus at his dictating station.

A general object of this invention may be stated to be the provision of novel marking apparatus under the direct control of a dictator operating in properly timed relation with a dictation recording machine situated at a point remote with respect to the marking apparatus and the dictator.

A further object of this invention is the provision of a combination of the above type which is, from the viewpoint of normal operation thereof, quite simple to operate and so interconnected as to ensure the production of an accurate marking chart which may with facility be used by the transcriber to aid him during the transcription of the sound record thus made.

The other objects of this invention, some of which will be directly referred to and others implied, will become apparent from the following detailed description of embodiments of the invention when taken in connection with the attached drawings illustrative of those embodiments.

This invention resides substantially in the combination, construction, arrangement, relative location of parts, steps and series of steps, all as will be explained in full detail hereinafter.

In the accompanying drawings,

Figure 1 is a diagrammatic view, with some parts broken away, illustrating one application of the principles of the invention herein disclosed.

Figure 2 is a diagrammatic view of a modified portion of the mechanism of Figure 1, representing an alternative thereof.

Figure 3 is a top plan view of the unit comprising the marking mechanism to be situated at the dictator's station.

Figure 4 is an end elevational view thereof.

Figure 5 is a plan view of a chart sheet which may be used with the device of Figures 3 and 4.

Figure 6 is a diagrammatic view, with some parts broken away, of a complete system resulting from the introduction into Figure 1 of the mechanism of Figure 2.

At the outset it is to be noted that although the invention will be described in detail as a device suitable for use with dictation recording machines, it will be apparent from the nature of the mechanism disclosed that its use is not so

limited. Likewise the description will be given more directly in relation to the application of the device of this invention to a dictation machine of the type disclosed in the co-pending application of Barton A. Proctor and Ferdinand C. W. Thiede, Serial No. 218,082, filed July 8, 1938. However, when fully understood it will become apparent that the subject matter of this invention is applicable to other types of sound recording machines, as for example those which make use of a cylindrical wax record tablet.

Prior to this invention there have been developed marking systems for use with dictation recording machines of such a nature that they 15 can be placed at a dictator's station remote from the sound recording machine itself. The marking index or record in such systems is, however, placed at the dictation machine and the control thereof is effected from the dictator's station by the operation of control devices.

In such systems some considerable effort is required to learn the accurate manipulation of the controls to produce the desired result, partly because of the number thereof and partly because of the fact that the effect of the 25 operation of these controls is not observable in normal use at the control point.

A further difficulty with such a system is that the results of the operation of the controls not 30 being strictly observable the dictator has no way of checking the instructions which he intended to give by the manipulation of the controls and, therefore, is led to uncertainty and often to the necessity of cluttering up the actual sound 35 record with additional instructions which undesirably diminish the capacity of the record tablet and serve to confuse the transcriber.

In the light of these difficulties an important 40 object of this invention may be emphasized by pointing out that the mechanism thereof places the record tablet at the control point where the dictator may observe at all times the record he is making thereon and may, when he so desires, make additional explanatory pencil notations.

It is a subsidiary object of this invention to 45 provide a record marking apparatus which is relatively simple to operate and simple for a novice to learn its operation.

In a general sense it may be stated that the 50 combination of this invention consists of marking apparatus operating in conjunction with the sound recording machine, even though they be widely spaced, in such manner that the dictator will know at all times the condition of the record

tablet. In other words, the dictator is provided with a visual indication of the amount of the record tablet used up, and the amount remaining. In addition, he has a visible indication of the various record data which he has recorded. This is all accomplished in such manner that any transcriber can take any record tablet and correction data sheet and reproduce a correct transcription of the recorded matter with ease.

To sum up and emphasize the simplicity of the control mechanism, for a combination in accordance with this invention, there is provided at the dictator's station a control for starting and stopping the machine, and easily distinguishable controls for making the correct indication marks on the record or correction sheet.

Referring to Figure 1 of the drawings, there is shown the mechanism of this invention in combination with a sufficient showing of a sound recording machine to establish the operative relationship therebetween in accordance with this invention. The full details of a sound recording machine of the type diagrammatically illustrated in Figure 1 are disclosed in the above-mentioned co-pending application.

It is to be noted that the sound recording portion of the apparatus is intended but need not necessarily be located at a point remote with respect to the dictator's station, and the portion of the mechanism to be placed therewith. A combination of this type is adapted particularly for use in large organizations where a central station is provided for a number of sound recording machines and provision is made throughout the adjacent offices for the operation thereof from any one of those offices. Each of the offices will be provided with the simple device illustrated in Figures 3 and 4, a sound pick-up device such as a microphone, and a small push-button control board.

As illustrated in Figure 1, the sound machine includes a vertical rotatable spindle 1, having a toothed support 2 on the upper end thereof upon, which a suitable record tablet 3 may be impaled for rotation thereof. As disclosed in the above-mentioned application, the record tablet may be in the form of a disc of thin, transparent cellulose acetate, smooth on both sides, and having a central aperture for interlocking engagement with the spindle 1.

The spindle 1 is journalled in a carriage 4 which is mounted for rectilinear movement back and forth on any suitable support (not shown). Connected to the carriage 4 is a threaded rod 6 which meshes with a worm wheel 5 secured on the shaft 1. The rod 6 is engaged by a threaded fixed half-nut 7 so that as the rod 6 revolves it will move to the right or left depending upon its direction of rotation. It may be provided on one end with a ratchet wheel or disc 8 engaged by a pawl mechanism 9 arranged to be operated by an electromagnet 10 controlled by switch 34, but since this invention is not concerned with this feature no further reference will be made to it.

The record tablet 3 is engaged on its under surface by a driving wheel 12 supported for rotation from a suitable power source not shown, and on its upper surface by means of a friction wheel 11 also journalled for rotation. As disclosed in the above-mentioned application, the friction wheel 11 is journalled on a support (not shown) so that the wheel may be moved into engagement with the record tablet 3, when it is desired to cause it to rotate, so as to hold it against the driving wheel 12.

The record tablet is engaged on its upper surface by the stylus of a sound recording device 13 which is diagrammatically illustrated as of the piezo-electric crystal type. The flexible record tablet 3 is backed up opposite the stylus by means of a hardened rotatable platen or anvil 14. In order to record with this device a fresh record tablet 3 is applied to the spindle 1 and the carriage 4 moved to the extreme right, in which position the stylus of the recording device 13 will engage the tablet at a point near its center. With wheel 12 revolving and wheel 11 in contact with the tablet 3, the tablet will be caused to revolve and as a result rod 6 will revolve through the interconnection of spindle 1 with rod 6 by the worm wheel 5.

The rotation of rod 6 will cause its traverse to the left because nut 7 is fixed. Thus carriage 4 will traverse to the left, carrying spindle 1 which is at the same time revolving on its longitudinal axis. As the sound recording device is operated, it being of course connected to a suitable pick-up device including a microphone, a spiral sound record will be impressed on the tablet 3 in the form of a plurality of successive convolutions of gradually increasing diameter until the record tablet is used up. The record groove will, of course, terminate at a point adjacent the periphery of the record tablet 3.

As shown, the carriage 4 is grounded. The lower end of spindle 1 is provided with a contact 15 for engagement once for every revolution of the spindle 1 with a contact 16 mounted on the carriage 4 on a suitable insulating support 17. Contact 16 is connected by wire 18 to one terminal of an electromagnet 18'. The other terminal of the magnet is connected by wire 18b to a suitable current source 33 which is grounded as shown. Magnet 18' operates a switch 18a one terminal of which is grounded and the other of which is connected by wire 18'' to a magnet 19. The other terminal of the magnet 19 is connected to wire 18b. The magnet 19 operates a pawl 20 which engages a ratchet wheel or disc 21 mounted on the end of a shaft 22. This shaft is journalled for rotation and is provided with a thread 23 of suitable size and pitch for a purpose to be described.

Mounted on a suitable support, such as a pair 50 of parallel rods 25 and 26, is a carriage or arm 24 which has a passage through it in which the threaded shaft 22 lies, without contacting it. The carriage 24 is connected by a spring 27 having one end fixed which acts to draw the carriage to the left. A pawl or finger 28 is mounted on the carriage 24 and engages the threads 23. Also mounted on the carriage 24 are the marking devices 29 and 30 which may be in the form of punches for the purpose of making holes through or marks in a correction tab or sheet 31 mounted thereunder. Returning to the magnet 10, it will be seen that one terminal is grounded while the other terminal is connected through a control switch 34 to the current source 33.

The mechanism comprising the elements 19, 20, 22, 24, 25, 26 and 31 and connected parts 65 comprises a simple unit which is to be mounted in a suitable housing 37 (see Figures 3 and 4) forming part of the device to be located at the dictator's station. This housing is part of a board or support 36 on which the record sheet 31 is to be placed when in use. When so placed it lies under the carriage 24 and the marking devices 29 and 30 mounted thereon. These consist of plunger-operated punches 29' and 30' re-

spectively, arranged so they may punch a hole in that part of the record sheet 31 over which they lie at the time they are operated. The record sheet 31 may be made of paper and has a series of vertical and horizontal lines in a preferred form as shown in Figure 5.

In use the sheet is folded along the line 35 so that the end portion thereabove lies directly under the portion below the line 35. Thus a hole punched in the sheet will go through both superposed parts of the sheet. When thus folded both the top and bottom parts of the sheet have two horizontal spaces which are provided with suitable indicia such as "Cor" to indicate correction marks and "Fin" to indicate finish marks. It will be seen that the marking device 29 traverses the correction space while the marker 30 traverses the finish space. The sheet 31 has a portion in which any additional notations may be made by the dictator. The unit shown in Figures 3 and 4 is placed at the dictator's station and is connected by wires to the dictation machine. There will, of course, be provided controls for starting and stopping the dictation machine which have not been shown as not being necessary to a disclosure of this invention.

In describing the operation of the complete system it will first be recalled how the dictation machine operates. The rotation of spindle 1 will cause the regularly intermittent engagement of contact 15 with contact 16. At each engagement a circuit will be completed from the grounded terminal of the current source 23 through the grounded carriage 4, spindle 1, contact 15, contact 16, wire 18, magnet 18', wire 18^b, back to the current source. Upon each energization of the magnet 18' switch 18^a will close, completing a circuit from the grounded side of the current source 33 through switch 18^a, wire 18'', magnet 19 and back to the current source 33.

Each energization of magnet 19 will cause the pawl 20 to impart a predetermined increment of rotation to the shaft 22 through the pawl and ratchet 20 and 21. The relay of which magnet 18' is a part should preferably be of the delayed release type so that its energization will not be of such a short duration that magnet 19 will not have an opportunity to correctly operate the pawl 20. Switch 18^a will be held closed sufficiently long so that pawl 20 may properly rotate the shaft 22. The resultant rotation of shaft 22 will permit the gradual traverse of the carriage 24 to the left in Figures 1 and 3, under the urging of spring 27. Thus the carriage 24 will move synchronously with the carriage 4 and the record tablet 3.

It follows, therefore, that the position of the carriage 24 is a direct indication of the relative position of the stylus of the recording device 13 on the record tablet 3. At any position of carriage 24 the dictator may, if he has a correction to follow in the dictation, operate the punch 29 to indicate that fact on the chart 31. If the dictator finishes a particular piece of dictation he may operate the punch 30 to indicate that fact and the relative point where it occurs. In addition he may add any explanatory notes on the bottom of the chart, as viewed in Figure 3, in the proper transverse position with respect to the relative point on the sound record to which it applies. When the carriage 24 has travelled completely across the chart 31 the record tablet 3 is full. The chart may then be removed from

its support and delivered to the transcription room, for attachment or other suitable association with its related record tablet.

At the time of transcription the transcriber will 5 tear off the portion above the line 35 which in practice may be perforated and apply it to a provided portion of the transcribing machine and the travelling pointer thereof so that as the record tablet is reproduced the pointer will traverse 10 the data sheet and give ample indication of the approach of corrections or of the finish of a particular piece of dictation. The transcriber will use the remaining portion of the chart for the additional notations on it. This portion will have 15 the same relatively positioned punch marks in it as did the smaller portion so that the relationship of the two parts may be easily ascertained.

When it is realized that the adjacent convolutions of the spiral record grooves on the record tablet 3 are spaced about 0.01 inch, in a practical embodiment of the machine, it will be seen that 20 the mechanism to be placed at the dictator's station must be extremely precise in construction and adjustment in order to cause synchronous 25 movement of the carriage 24 with respect to the carriage 4 when using the mechanism so far described. In order to eliminate this problem, which is a problem only in that it adds to the expense of the machine, the modified structure 30 of Figure 2 is provided.

As illustrated in Figure 2, the mechanism includes the magnet 18' with its wire 18 which is intended to be connected to the contact 16. The magnet 18' of Figure 2 is the same magnet as that 35 bearing the same number in Figure 1 and will of course take its place. One contact of switch 18^a is grounded as before, while the other contact is connected by the wire 18^c to a magnet 40, the other terminal of which is connected to the 40 grounded power source 33. Likewise the other terminal of magnet 18' is connected to this source as shown by the wire 18^b. When magnet 40 operates, a pawl 41 engages a ratchet wheel 42 to move it in a clockwise direction. The ratchet wheel 42 is free to rotate on a shaft 43 but is 45 connected thereto by a spring 44.

A contact arm 45 is connected to the ratchet wheel 42 for rotation with it. The shaft 43 is connected to one terminal of a magnet 46, the other terminal of which is connected to the wire 18^b. Magnet 46 operates a pawl 50 which also cooperates with the ratchet wheel 42 in a manner so as not to prevent rotation of the ratchet wheel 42 in a clockwise direction by the pawl 41. 55 However, the pawl 50 holds the ratchet wheel against counter-clockwise rotation as long as it is in engagement therewith.

A contact positioned to be engaged by the contact finger 45 is connected to wire 18'' which 60 will be connected to the same terminal of magnet 19 as is the wire 18'' of Figure 1. The other terminal of magnet 19 will be connected to the current source 33 as before. Likewise, as before, the relay of which magnet 18' is a part is of the delayed release type. Figure 6 diagrammatically illustrates the system of Figure 1 as modified by the addition of the mechanism of Figure 2, as explained above.

In beginning the description of the operation of this modification it will be noted that shaft 43, the ratchet 42, and contact finger 45 while all in conducting relation are insulated from the other parts of the machine, that is to say, are not grounded. Obviously, of course, the pawls 41 and 50 are not to be grounded as will be appar-

ent from an examination of the circuits. As the recording machine operates and contacts 15 and 16 engage at regular intervals, magnet 18' will be energized, as before, with the result that switch 18^a will intermittently close, and magnet 40 will be intermittently energized.

Upon deenergization thereof the pawl 41 will cause the step-by-step clockwise rotation of the ratchet wheel 42 and contact finger 45 putting spring 44 under gradually increasing tension. Pawl 50 will prevent the reverse rotation of the ratchet wheel 42 and finger 45. As arranged contact finger 45 will not engage the contact connected to wire 18'' until the tenth impulse or energization of magnet 40. Upon the tenth impulse contact finger 45 will complete the circuit including wire 18'', causing energization of the magnet 19 and hence a single step movement of shaft 22 in the desired amount.

It will be seen that magnet 46 will be in circuit with magnet 19 at the time the circuit is completed, with the result that pawl 50 is pulled out of engagement with the ratchet wheel 42. However, the ratchet wheel 42 is still not released because it is held against counter-clockwise rotation by the pawl 41 because the energization of magnet 46 is maintained a predetermined period of time as a result of the fact that relay 18' is of the delayed release type. Thus adequate time is allowed for the complete actuation of shaft 22 by the pawl 20. However upon the deenergization of the magnet 46 at switch 18^a pawl 41 will release the ratchet wheel 42 with the result that tensioned spring 44 will snap the ratchet 42 and contact finger 45 back to initial position, breaking the circuit to magnet 19. Thus the carriage 24 will only be given an increment of movement one step for every ten revolutions of the record tablet 3.

By properly proportioning the parts, the movement of carriage 24 in each step may be any desired amount within reasonable limits. The accuracy of construction of the mechanism for advancing the carriage 24 need not therefore be as great as in the previous arrangement without interfering with the correct functioning of the apparatus. It is apparent, of course, that when a new record tablet 3 is placed on the recording machine the carriage 24 may be readily moved back to its starting position at the right, because pawl 28 may ride over the threads 23 in the reverse direction. In accordance with well known principles a spring (not shown) may act on the pawl 28 to ensure proper functioning thereof.

From the above description it will be apparent to those skilled in the art that the principles of this invention are capable of embodiment in various physical forms. I do not, therefore, desire to be strictly limited to the disclosure as given for purposes of illustration, but rather to the scope of the appended claims.

What is claimed is:

1. In a machine of the type described, the combination including means for supporting a record tablet on which a record is to be made, means for impressing a record on said tablet, means for causing relative movement of said means, a marking mechanism, and electrical means interconnecting said marking mechanism with said record supporting means and operated as a result of said relative movement for indicating at a remote point the relative position between said first two means.

2. In a machine of the type described, the combination including means for supporting a record

tablet on which a record is to be made, means for impressing a record on said tablet, means for causing relative movement of said means, a marking mechanism, and means interconnecting said marking mechanism with said record supporting means for indicating at a remote point the relative position between said first two means, said marking means including a pair of independently operable marking devices for recording two sets of data relative to the record on the tablet.

3. In a machine of the type described, the combination including a carriage having a rotatable record tablet support, a sound recording device for impressing a record on the tablet, means for effecting movement of said carriage with respect to the sound recording device, a marking device to be positioned remotely with respect to said prior mechanism, and electromagnetically controlled means operated by said rotatable support for effecting simultaneous movement of said marking means.

4. In a machine of the type described, the combination including a carriage for supporting a record tablet, a sound recording device for impressing a record on the tablet, means for effecting movement of said carriage with respect to the sound recording device, a marking device to be positioned remotely with respect to said prior mechanism and electromagnetically controlled means operated by said means for moving the carriage for imparting step-by-step movement of the marking means in timed relation to the movement of said carriage.

5. In a machine of the type described, the combination including a rotatable support for a record tablet, a sound recording head positioned to engage the record tablet when supported on said support, means for effecting relative movement between said record support and said sound recording head, a marking device adapted to be positioned at a point remote with respect to said record tablet support, means for operating said marking device, and means for energizing said marking device operating means with successive impulses, one for each rotation of the record tablet support.

6. In a machine of the type described, the combination including a rotatable record support, a sound recording head, means for effecting relative movement between said record support and sound recording head, a marking device, electromagnetic means for effecting step-by-step movement of the marking device, and means operated by the rotatable support for repeatedly energizing said electromagnetic means as the record tablet revolves, whereby the instantaneous relative position between the recording head and the record tablet is indicated by the marking device.

7. In a machine of the type described, the combination including a rotatable record support, a sound recording head, means for effecting relative movement between the record support and the sound recording head, a switch operated by the record support so as to be closed for each revolution thereof, a marking device, and means for effecting operation of the marking device in timed relation to the movement of the record support including means for storing a predetermined number of impulses whereby the marking device is given an increment of movement for a predetermined number of revolutions of the record support.

8. In a machine of the type described, the combination including a carriage having a record support journaled thereon, means for causing

movement of said carriage, a sound recording head positioned to engage the record tablet when mounted on said record support, a control device operated intermittently once for each revolution of said record support, a marking device, and means controlled by said control device for operating said marking device in timed relation with said carriage.

9. In a machine of the type described, the combination including a carriage having a record support journaled thereon, means for causing movement of said carriage, a sound recording head positioned to engage the record tablet when mounted on said record support, a control device operated once for each revolution of said record support, a marking device, and means controlled by said control device for operating said marking device in timed relation with said carriage, said marking device including a rotatably supported threaded shaft, a carriage slidably mounted with respect to said threaded shaft, and means interconnecting the threaded shaft with said carriage whereby rotation of the threaded shaft causes movement of said carriage.

10. In a machine of the type described the combination including a fixed recording head, a movable carriage, a rotatable record supporting spindle mounted on said carriage, a marking device supported for movement with respect to a chart, means for causing movement of said marking device, and means operated by said spindle for energizing said last means whereby the marking device moves with respect to the chart in timed relation to the relative movement between the carriage and the head.

11. In a machine of the type described, the combination with a sound recording device including a fixed recording head and means for supporting a record tablet, said means being relatively movable with respect to said head, of marking means including a marking device remotely situated with respect to the sound recording device, means op-

erated by said supporting means for moving the marking device in timed relation with said support, said marking device serving to indicate the position of the recording head on the record tablet, and means at the sound recording device and connected to the marking device for operating the marking device at will.

12. In a machine of the type described, the combination including means for supporting and rotating a record tablet, a sound recording device positioned to engage the record tablet to impress a sound record thereon, means for effecting relative movement between both of said means, a marking device adapted to be situated remotely with respect to said previous elements, means for operating the marking device to indicate the instantaneous relative position between said recording device and the record tablet, and means operated by said means for effecting said relative movement to energize said last means.

13. In a machine of the type described, the combination including a fixed recording head, a movable carriage, a rotatable record supporting spindle mounted on said carriage, a marking device supported for movement with respect to a chart, means for causing movement of said marking device, and means including an energizing device operated by said spindle for energizing said last means once for each rotation of said spindle.

14. In a machine of the type described, the combination including a fixed recording head, a movable carriage, a rotatable record supporting spindle mounted on said carriage, a marking device supported for movement with respect to a chart, means for causing movement of said marking device, and means operated by said spindle for energizing said last means so that the marking device is given one increment of movement for a predetermined plurality of revolutions of said spindle.

HENRY P. CLAUSEN.
